HEADER SUPPORT MECHANISM FOR HARVESTERS

Roy L. Bell, Kahlutus, Wash.

Application September 19, 1957, Serial No. 685,034

5 Claims. (Cl. 56—209)

My invention relates to a header support mechanism for harvesters. It is now common in push type self propelled combine harvesters that are used in hillside areas to swivel the header with respect to the separator in order that the header may follow the ground contour while the separator remains upright. In most cases the pivot connection is made at the point where the header spout connects to the header. Examples of this construction are found in the U.S. patent to Harp, No. 2,753,675, and the U.S. patent to Kroll and Farber No. 2,780,903. In these constructions with which I am familiar a ring of channel shape is mounted on a header and roller supporting units fit inside the channel to carry the header, the roller supporting units being mounted on the header spout, or the situation is reversed and the roller supporting units are mounted on the header and run in the channel of a ring mounted on the header spout. In either event it has been found that because of the peculiar loading of this swivel connection the bearing members wear out rapidly. They are, of course, subjected to a great deal of abrasion by the dirt and dust particles and thus far it has been very difficult to maintain the bearings in good condition.

It is the purpose of my invention to provide a novel support means whereby bearings in the header spout to header connection are relieved of the tremendous load of the header and the tendency to tip is taken up by additional bearing members so located as to be substantially free of the accumulation of dust and abrasive material that interfere with the bearings normally used.

The nature and advantages of my invention will appear more fully from the following description and the accompanying drawings wherein the application of my invention is illustrated in two equivalent forms. The drawings and description are illustrative only, however, and are not intended to limit the invention except insofar as it is limited by the claims.

In the drawings:

Figure 1 is a plan view with parts broken away looking down on the header and header spout of the type to which my invention is applied.

Figure 2 is a sectional view taken substantially on the line 2—2 of Figure 1;

Figure 3 is an enlarged fragmentary front view with parts broken away and parts shown in section showing the connection between the header and the header spout with my invention applied thereto;

Figure 4 is an enlarged fragmentary front view with parts broken away and with parts in section showing a modified construction of my invention;

Figure 5 is a sectional view taken on the line 5—5 of Figure 3 and on an enlarged scale;

Figure 6 is a sectional view taken on the line 6—6 of Figure 4 and on an enlarged scale; and

Figure 7 is an enlarged sectional view taken through one of the bearing members used in my invention on a plane which includes the axis of the bearing member.

Referring now to the drawings, the header to header

2

spout connection shown in Figures 1 and 2 is essentially like that of the Harp patent hereinbefore referred to wherein an outer annular ring member 10 is secured to the header frame 9 so as to support it and an inner channel shaped ring member 11 is secured to the header spout 8. The members 10 and 11 are concentric and as shown in the Harp patent above referred to, there are bearing members carried by the ring member 10 that ride in the channel of the ring member 11. The header is turned or rotated with respect to the header spout by a jack 7 which is opposed by a spring 6. The drive mechanism for the header embodies a drive chain 5 and shafting indicated at 4 to operate the various parts of the header which have to be driven. It will be observed that the weight of the header is practically all forward with respect to the connection between the ring members 10 and 11. This imposes a tremendous strain on the bearing members. The swivel connection established by these members accumulates dirt from the field and it is very difficult to obtain access to the bearings. The result is that the bearings have a very short life and they are difficult to replace.

According to my invention I provide means for eliminating most of the excessive strain on the bearings due to the unbalanced loading in such a way the bearings can be allowed to perform their normal function under much lighter load and act really as guides and not as load carrying members. In order to accomplish this result, I provide one of the ring members 10 or 11 with an arcuate ledge on both sides and I provide the other ring member with free running rollers riding on the ledges. As illustrated in Figures 3 and 5, the inner ring member 11 which is channel shaped, has ledges 12 and 13 thereon. These ledges are placed at the outer rim of the channel shaped ring member 11 and are extended far enough from the top center of the ring member 11 in both directions around the ring member 11 to support rollers 14 and 15 within the limits to which the header frame 9 may turn with respect to the spout 8. The outer ring member 10 of the swivel connection is strengthened by an inverted channel shaped piece 16 and the rollers 14 and 15 have their stub shafts 17 and 18 bolted to the outer ring member 10 where it is strengthened by the piece 16. The ledges 12 and 13 are reinforced by gussets 19 that are welded in place.

The equivalent form of the invention shown in Figures 4 and 6 utilizes the same rollers 14 and 15 but in this case the inner channel shaped ring member 11 is reinforced by bars 20 and the shafts 17 and 18 of the rollers 14 and 15 are threaded into the members 20 at the top of the ring member 11 on the header spout 8. The ring member 10 is provided with ledges 21 and 22 extending forwardly and rearwardly from this member and the ledges are reinforced by gussets 23 and 24 which are welded in place. In this case the rollers 14 and 15 support the ledges 21 and 22 and the weight of the header is transmitted from the ledges 21 and 22 down through the rollers to the ring member 11 which is mounted on the header spout. In the form of the invention shown in Figures 3 and 5, the rollers 14 and 15 ride on the ledges 12 and 13, the rollers in this case being carried by the ring member 10 on the header and transmitting their load to the ring member 11 which is fixed to the header spout.

With my invention applied to the connection between the header and spout of the combine, whether it be in the form shown in Figures 3 and 5 or the form shown in Figures 4 and 6, the weight of the header is primarily borne by the rollers 14 and 15 and the ledges 12, 13, or 21 and 22. These rollers are not only load supports but, being set forward of and rearwardly of the ring members 10 and 11, they prevent tilting of one ring member

with respect to the other. The bearing units 25 between the ring members 10 and 11 are relieved of the binding action that the tilting caused. The bearing units 25, being offset to the right and the left of the vertical center line 5—5 in Figure 3 and 6—6 in Figure 4 of the header to header spout connection oppose any swing of the header about this center line due to greater opposition to advance at one end or the other of the header. The combination of the supporting rollers 14 and 15 with the ring members 10 and 11 and their internal bearing units 25 therefore provides a stable, long life connection between the header spout and the header.

The rollers 14 and 15 are constructed as illustrated in Figure 7 of the drawings. The outer shell 26 of the bearing is carried by a roller bearing 27 which is pressed on the stub shafts 17 and 18. These shafts have provision at their outer ends for oiling as indicated at 28. The rollers 14 and 15 are exposed where they are readily serviced and where dirt cannot accumulate between them and the ledges with which they engage.

Having thus described my invention, I claim:

1. In a header to separator connector of a harvester wherein the header has a part which is rotatably mounted upon a part affixed to the separator for rotation about an axis extending transverse to the header, the improvement comprising two ledges affixed to one of the parts above said axis and having bearing surfaces concentrically curved about said axis, one ledge being extended forwardly from the part and the other ledge being extended rearwardly from the part, and two rollers journaled on the other part on axes parallel to said axis, one roller bearing on one of said surfaces and the other roller bearing on the other surface.

2. In a header to separator connection of a harvester wherein the header has a part which is rotatably mounted upon a part affixed to the separator for rotation about an axis extending transverse to the header by a pair of ring members, one ring member being on the part affixed to the separator, the other ring member being on the part affixed to the header, and bearings interposed between said ring members laterally outward from the axis, the improvement comprising a forwardly extending ledge on the ring member on the part affixed to the separator, said ledge being curved concentrically with the last named ring member and mounted thereon, a shaft secured to the other ring member and extending over the ledge, and a roller journaled on the shaft, said roller riding on the ledge and rolling thereon as the header turns on said axis with respect to the separator.

3. In a header to separator connection of a harvester wherein the header has a part which is rotatably mounted upon a part affixed to the separator for rotation about an axis extending transverse to the header by a pair of ring members, one ring member being on the part affixed

to the separator, the other ring member being on the part affixed to the header, and bearings interposed between said ring members laterally outward from the axis, the improvement comprising a forwardly extending ledge on the ring member on the part affixed to the header, said ledge being curved concentrically with the last named ring member and mounted thereon, a shaft secured to the other ring member and extending beneath the ledge, and a roller journaled on the shaft, said roller engaging the ledge and supporting it as the header turns on said axis with respect to the separator.

4. In a header to separator connection of a harvester wherein the header has a part which is rotatably mounted upon a part affixed to the separator for rotation about an axis extending transverse to the header by a pair of ring members, one ring member being on the part affixed to the separator, the other ring member being on the part affixed to the header, and bearings interposed between said ring members laterally outward from the axis, the improvement comprising a forwardly extending ledge on the ring member on the part affixed to the separator, said ledge being curved concentrically with the last named ring member and mounted thereon, a shaft secured to the other ring member and extending over the ledge, a roller journaled on the shaft, said roller riding on the ledge and rolling thereon as the header turns on said axis with respect to the separator, a rearwardly extending ledge on the ring member on the part affixed to the separator, said ledge being curved concentrically with the last named ring member, a shaft secured to the other ring member and extending over the last mentioned ledge and a roller journaled on the last mentioned shaft.

5. In a header to separator connection of a harvester wherein the header has a part which is rotatably mounted upon a part affixed to the separator for rotation about an axis extending transverse to the header by a pair of ring members, one ring member being on the part affixed to the separator, the other ring member being on the part affixed to the header, and bearings interposed between said ring members laterally outward from the axis, the improvement comprising a rearwardly extending ledge on the ring member on the part affixed to the separator, said ledge being curved concentrically with the last named ring member and mounted thereon, a shaft secured to the other ring member and extending beneath the ledge, and a roller journaled on the shaft, said roller engaging the ledge and rolling thereon.
